(57) **CLAIM**

The ornamental design for a paper product dispenser, as shown and described.

DESCRIPTION

FIG. 1 is a front perspective view of a first embodiment of a paper product dispenser having a removable, cut-out section showing our new design;

FIG. 2 is a front view of the dispenser shown in FIG. 1;
FIG. 3 is a back view of the dispenser shown in FIG. 1;
FIG. 4 is a right side view of the dispenser shown in FIG. 1;
FIG. 5 is a left view of the dispenser shown in FIG. 1;
FIG. 6 is a top side view of the dispenser shown in FIG. 1; and,

FIG. 7 is a bottom view of the dispenser shown in FIG. 1. The short broken lines are used to show visible environmental structures forming no part of the claimed design and dash-dot-dot lines define the bounds of a claimed design. Long dashed lines represent score/pre-cut lines for the removable, cut-out section.
